N-PHENETHYL-BETA-ALANINE
DERIVATIVES

Richard Baltzly and Arthur P. Phillips, New York,
N. Y., and Lowell O. Randall, Nutley, N. J., as-
signors to Burroughs Wellcome & Co. (U. S. A.)
Inc., New York, N. Y., a corporation of New
York

No Drawing. Application June 21, 1947,
Serial No. 756,335

5 Claims. (Cl. 260—471)

1

The present application is a continuation-in-part of our co-pending application Serial Numbers 528,448 and 528,449, both filed March 28, 1944, and both now abandoned.

Our invention relates to certain N-phenethyl-beta-alanine derivatives and is based on the discovery that certain N-phenethyl-beta-alanine esters and alkylolamides have valuable physiological properties, especially in stimulating uterine smooth muscle without acting as general pressor drugs, combined with low toxicities.

One group of compounds of this type showing considerable potencies are the compounds in which the phenyl ring is connected to the nitrogen by a pure hydrocarbon chain, and the phenyl ring bears two ethereal oxygen substituents, such as two methoxy groups or a methylene dioxy group, these substances forming the subject matter of our simultaneously filed companion application Serial No. 756,336 filed June 21, 1947.

Another group of active substances consists of the N-phenethyl-beta-alanine esters in which the beta-carbon of the phenethyl group (counting from the nitrogen atom) is substituted with hydroxyl, with or without methyl or alkoxy substituents in the phenyl ring.

These compounds which form the subject matter of the present invention may be represented by the general formula:

in which R^1 is a member of the group consisting of hydrogen and methyl, R^2 is a straight chain alkyl containing from 1 to 5 carbon atoms and R^3 and R^4 are members of the group consisting of hydrogen, methyl, methoxy and ethoxy.

The compounds according to the invention as represented in the general formula above, are tertiary amines which may be combined with various acids to form salts for convenience in handling and stability. The nature of the acids forming these acid salts of the tertiary amines is ordinarily of no importance for the physiological properties but may influence the ease of crystallization or purification. Thus in most cases salts of hydrochloric acid are at least as satisfactory as salts of other acids, but some compounds have been isolated more readily as sulfates, phosphates, tartrates, malates, succinates, hydrobromides, etc. Such variations in the salts employed for the manipulations of organic bases are common and, when useful, ob-

2

vious, and we neither consider any part of our invention to consist therein nor do we conceive that any absence of mention of the use of such common acids shall be held to limit the invention.

5 The claims appended hereto are intended to cover the tertiary bases as well as their acid salts.

10 The physiological properties of the type displayed by the present family of compounds are not shown by N-benzyl or N-substituted benzyl beta-alanine esters or by variously substituted N-phenethyl glycine esters or N-phenethyl alpha-alanine esters. It is thus apparent that the chain of two carbon atoms between the aromatic ring and the basic nitrogen is essential as is also the chain of two carbon atoms between the nitrogen atom and the carbalkoxyl group.

15 The tertiary bases according to the general formula are obtained by either of two general methods. In the first of these, the appropriate phenyl alkanolamine, in relation to the preceding general formula, to be represented as

20 30 is reacted with a beta-halogeno, usually a beta-bromopropionic ester. This reaction is not unsatisfactory but since a separation of basic substances is necessary and since only half (at most) of the more valuable intermediate can be utilized we prefer a second line of synthesis.

According to this second method the amine is treated with an excess of an ester of acrylic acid, usually methyl acrylate, the reaction being in the sense of the equation:

40 45 50 55 The product so obtained is a tertiary base. The bases so obtained can be converted into the desired salts by methods generally known in the art. The nature of the acid employed is ordinarily of minor importance for the physiological action but certain salts have physical properties making them more or less advantageous for purification. In most cases the chlorides have been used and they are generally preferred but other salts, such as the bromides, iodides, phosphates,

sulfates, oxalates, tartrates, succinates, malates, etc., have at times proved convenient.

The amines used in the preparation of the compounds according to the invention are well known in the art and their preparation does not form any part of the present invention.

Although other esters of acrylic acid than the methyl ester may be used in the second line of synthesis, methyl acrylate is the most readily available and has generally been employed. The conversion of the beta-alanine methyl esters into higher alkyl esters (corresponding to variations in R^2) can be accomplished conveniently by heating the methyl ester in a large excess of the appropriate higher alcohol containing anhydrous hydrogen chloride under a fractionating column. During several hours heating, distillate is allowed to pass over gradually and an ester exchange takes place in the solution, the alkyl group of the higher alcohol replacing the methyl group in the ester.

The following list of compounds prepared according to the invention is given by way of illustration, but is not intended as a limitation except as expressed in the claims:

1. N-methyl-N-(beta-hydroxy-beta-4-methylphenylethyl) beta-alanine methyl ester acid malate.
2. N-methyl-N-(beta-hydroxy-beta-2,5-dimethylphenylethyl) beta-alanine methyl ester hydroiodide.
3. N-methyl-N-(beta-hydroxy-beta-2,5-dimethoxyphenylethyl) beta-alanine methyl ester hydrochloride.
4. N-methyl-N-(beta-hydroxy-beta-2,5-dimethoxyphenylethyl) beta-alanine ethyl ester hydrochloride.
5. N-methyl-N-(beta-hydroxy-beta-2,5-dimethoxyphenylethyl) beta-alanine n-butyl ester acid oxalate.
6. N-methyl-N-(beta-hydroxy-beta-2,5-dimethoxyphenylethyl) beta-alanine n-amyl ester acid oxalate.
7. N-methyl-N-(beta-hydroxy-beta-3,4-dimethoxyphenylethyl) beta-alanine methyl ester acid oxalate.
8. 1-N-methyl-N-(beta-hydroxy-beta-3,4-dimethoxyphenylethyl) beta-alanine methyl ester acid oxalate.
9. N-methyl-N-(beta-hydroxy-beta-3,4-dimethoxyphenylethyl) beta-alanine ethyl ester hydrobromide.
10. N-methyl-N-(beta-hydroxy-beta-2,5-dimethoxyphenylethyl) beta-alanine methyl ester hydrochloride.
11. N-methyl-N-(beta-hydroxy-beta-phenylisopropyl) beta-alanine methyl ester hydrochloride.
12. N-methyl-N-(beta-hydroxy-beta-phenylisopropyl) beta-alanine ethyl ester hydrochloride.
13. 1-N-methyl-N-(beta-hydroxy-beta-phenylisopropyl) beta-alanine ethyl ester hydrochloride.
14. N-methyl-N-(beta-hydroxy-beta-2-methoxy-5-methylphenylisopropyl) beta-alanine methyl ester hydrochloride.
15. N-methyl-N-(beta-hydroxy-beta-3,4-dimethoxyphenylisopropyl) beta-alanine methyl ester hydrochloride.
16. d-N-methyl-N-(beta-hydroxy-beta-3,4-dimethoxyphenylisopropyl) beta-alanine methyl ester hydrobromide.
17. N-methyl-N-(beta-hydroxy-beta-3,4-dimethoxyphenylisopropyl) beta-alanine ethyl ester hydrochloride.

18. N-methyl-N-(beta-hydroxy-beta-3,4-dimethoxyphenylisopropyl) beta-alanine n-butyl ester acid sulfate.

The following examples may serve to illustrate the methods used in preparing the compounds according to the invention but are not intended to limit the invention in any way.

EXAMPLE 1

N-methyl-N-(beta-hydroxy-beta-2,5-dimethoxyphenylethyl) beta-alanine ethyl ester hydrochloride

Seventeen g. of beta-hydroxy-beta-(2,5-dimethoxy-phenyl)-ethylmethylamine hydrochloride (for preparation see Baltzly and Buck, J. Am. Chem. Soc. 62, 164 (1940)) was dissolved in water. The solution was basified and the liberated base was taken into benzene and dried over potassium carbonate. The solution in about 200 cc. of benzene was allowed to stand sixty-four hours with 45 g. of methyl acrylate and was then warmed on the steam-bath one-half hour. The solution was cooled and poured into acetone to which had been added 10 g. of a solution of hydrogen chloride in methanol (39% by weight). Absolute ether was added until the solution was not quite turbid. There crystallized 21 g. of the hydrochloride of N-methyl-N-(beta-hydroxy-beta-2,5-dimethoxyphenylethyl) beta-alanine methyl ester melting at 154.5-155° C. A recrystallization from methanol-acetone-ether mixture raised the melting point to 156-156.5° C., the product then weighing 20.5 g.

EXAMPLE 2

N-methyl-N-(beta-hydroxy-beta-2,5-dimethoxyphenylethyl) beta-alanine ethyl ester hydrochloride

Three g. of the corresponding methyl ester obtained according to Example 1 was dissolved in 100 cc. of absolute ethanol to which was added 10 g. of 35% (by weight) ethanolic hydrogen chloride. The solution was refluxed four hours under a fractionating column permitting slow distillation. The solution was then evaporated nearly to dryness, diluted with ethyl acetate and ether and cooled. Colorless needles separated which melted at 125-6° C. Further crystallization did not raise the melting point and the analysis was correct for the ethyl ester hydrochloride.

EXAMPLE 3

N-methyl-N-(beta-hydroxy-beta-2,5-dimethoxyphenylethyl) beta-alanine n-butyl ester acid oxalate

Five g. of the corresponding methyl ester obtained according to Example 1 was refluxed in n-butyl alcohol containing dissolved hydrogen chloride by the method of Example 2. The resulting n-butyl ester hydrochloride did not crystallize readily and the product was most readily purified as the acid oxalate.

EXAMPLE 4

N-methyl-N-(beta-hydroxy-beta-3,4-dimethoxyphenylethyl) beta-alanine methyl ester acid oxalate

Fifteen g. of beta-hydroxy-beta-(3,4-dimethoxyphenyl) ethylmethylamine (B. P., 152° at 1 mm.) was reacted by the method of Example 1 with 50 g. of methyl acrylate. The hydrochloride proved not to be readily crystallized and the product was transformed to the acid oxalate.

which crystallized from aqueous acetone-ether mixtures forming flattish prisms, M. P., 127-128° C.

EXAMPLE 5

N - methyl - *N* - (beta - hydroxy - beta - phenylisopropyl) beta-alanine methyl ester hydrochloride

One tenth mole (16.5 g.) of d-1 ephedrine was dissolved in benzene. To this were added 12.7 g. (0.15 mole) of methyl acrylate. This mixture was allowed to stand over night and then refluxed one hour. On addition of methanolic HCl there separated a syrup which soon solidified and was purified by recrystallization from acetone-ether mixture. Analysis showed it to be *N*-methyl-*N*-(beta-hydroxy-beta-phenylisopropyl) beta-alanine methyl ester hydrochloride.

EXAMPLE 6

N - methyl - *N* - (beta - hydroxy - beta - phenylisopropyl) beta-alanine ethyl ester hydrochloride

Fifteen g. of d-1 ephedrine hydrochloride was dissolved in water. The solution was basified and the ephedrine base was extracted with ether, the extract being dried over potassium carbonate. The ether was evaporated and to the residue (10.2 g.) was added 11.2 g. of ethyl beta-bromo-propionate dissolved in 30 cc. of absolute ethanol. The solution was refluxed six hours and the ethanol was evaporated. The residue was dissolved in dilute hydrochloric acid, cooled and treated with a solution of 6 g. of sodium nitrite. The resulting nitroso derivative of the previously unreacted ephedrine was removed by extraction with ether and discarded. The aqueous layer was made strongly alkaline, extracted with ether and the ethereal extracts were dried over potassium carbonate. The ethereal solution was filtered from the desiccant and poured into an excess of hydrogen chloride dissolved in absolute alcohol. The hydrochloride of *N*-methyl-*N*-(beta-hydroxy-beta-phenylisopropyl) beta-alanine ethyl ester crystallized immediately.

EXAMPLE 7

1-*N*-methyl-*N*-(beta-hydroxy-beta-phenylisopropyl) beta-alanine ethyl ester hydrochloride

By the method of Example 6, 1-ephedrine was reacted with ethyl acrylate to yield the desired product.

EXAMPLE 8

N - methyl - *N* - (beta - hydroxy - beta - 2 - methoxy-5-methylphenyl isopropyl) beta-alanine methyl ester hydrochloride

Five g. of beta-(2-methoxy-5-methylphenyl)-beta-hydroxy isopropyl methylamine hydrochloride (for preparation see Ardis, Baltzly and Schoen, J. Am. Chem. Soc. 68, 591 (1946)) was

dissolved in water. The base was liberated and treated with 5.1 g. of methyl acrylate according to the method of Example 1. The product, obtained in 84% yield, was crystallized from methanol-acetone-ether mixtures and melted at 179-180° C.

We claim:

1. A new composition of matter selected from the group consisting of the compounds having the following general formula:

15 in which R^1 is a member of the group consisting of hydrogen and methyl, R^2 is a straight chain alkyl containing from 1 to 5 carbon atoms and R^3 and R^4 are members of the group consisting of hydrogen, methyl, methoxy and ethoxy, and the salts thereof.

2. A new composition of matter selected from the group consisting of the compounds having the following general formula

in which R^2 is a straight chain alkyl containing from 1 to 5 carbon atoms and R^3 and R^4 are members of the group consisting of hydrogen, methyl, methoxy and ethoxy, and the salts thereof.

3. A new composition of matter selected from the group consisting of the compounds having the following general formula:

35 in which R^2 is a straight chain alkyl containing from 1 to 5 carbon atoms, and the salts thereof.

4. *N* - methyl - *N* - (beta - hydroxy - beta - 2,5-dimethoxyphenylethyl) beta-alanine methyl ester hydrochloride.

45 5. *N* - methyl - *N* - (beta - hydroxy - beta - 3,4-dimethoxyphenylethyl) beta-alanine methyl ester acid oxalate.
